UNITED STATES PATENT OFFICE

HANS CHRISTIAN HANSEN, OF FREDERIKSBERG, DENMARK, ASSIGNOR TO SOREN WISTOFT & CO.'S FABRIKKER, AKTS., OF COPENHAGEN, DENMARK

RELEASING MECHANISM FOR AUTOMATIC VENDING MACHINES

Application filed June 24, 1929, Serial No. 373,365, and in Denmark July 19, 1928.

The invention relates to a releasing mechanism for an automatic vending machine, which can distinguish between coins with flange and coins without flange and is of the 5 type, which with this object in view has a pair of spring-actuated feelers, formed as double-armed levers, with beaks turned towards each other, between which the coins inserted into the machine fall.

10 The releasing mechanism is essentially characterized by the said two feelers being suspended on stationary pins, and below, but a little to one side of the gap between the two opposite feeler beaks a stop member being 15 provided, against which a coin inserted into the machine will strike, and which has the effect that the coin if it has no flange, rolls so that it falls down to the one side of a partition whereupon it is in a suitable manner conducted out of the machine, whereas 20 if the coin has a flange it rolls and moves in such a manner, guided both by the feelers seizing within the flange and by the said stop member, that this effects an opening of 25 the feelers, and then falls down along the other side of the said partition, so as to release in the usual manner the locking mechanism of the opening member of the machine.

In the drawing

30 Fig. 1 shows the part of the releasing mechanism in question, which is necessary for understanding the invention, and

Fig. 2 the same, seen from the left side in Fig. 1.

35 1 is the usual, slanting coin chute along which a coin inserted into the respective machine rolls down to and into a vertical downwards coin passage 2, which is situated between two stationary plates 3, and which at 40 the sides (on the right and on the left in Fig. 1) are limited in a suitable manner. In the constructional form shown the coin passage 2 is limited on the right side (Fig. 1) by the inner edge 4 of a strip of plate 5 secured between the plates 3, which reaches

a little beyond the under edges of the plates 3. At its lower end the strip of plate 5 has the shape of an angle in such a manner that it forms an arm 6, which passes in under a part of the lower opening of the coin passage 2. To the arm 6 there is pivotally suspended a small pawl 7, having the cross-section of an inverted U, so that this pawl may easily be turned up from its normal position shown in the drawing, which the pawl will again 50 assume by gravity, when it no more is under an action turning it in the said direction. The under edges of the pawl have on the greater part of their length, reckoning from the free end of the pawl, flat surfaces 8, 55 which extend slantingly upwards in direction to this end.

9 are the two feelers formed as double armed levers. Each feeler is pivotal on a stationary pin 10 and under the effect of a coiled spring 11. The two pins 10 are situated a little sideways, each opposite one of the plates 3. The lower parts of the feelers are bent in a direction towards one another, while the feelers are thus convergent downwards towards each other, their said inwardly bent parts normally (under action of the springs 11 on the respective feelers) each abut against the lower outer side edge of the plate 3, and the beaks 12 of the feelers are then 65 beneath the coin passage 2 at a short distance from same and are at a distance from each other which is practically equal to the thickness of a coin, for which the machine is intended, within its flange. The outer end of 70 the pawl 7 is a little to one side of the gap between the beaks 12 of the feelers, and it may be mentioned, that its upper surface has a slight incline towards the vertical middle plane common to the feelers.

13, Fig. 1, is a stationary partition arranged at a suitable place in the machine casing.

The mode of operation is the following:

It shall be assumed that a coin for which

the machine is intended, is inserted into the machine (a coin with flange). After having rolled down through the coin chute 1, the coin falls down through the coin passage 2 with its flange first against the beaks 12 of the feelers. In consequence of its kinetic energy the coin will turn the feelers so much against the action of the spring 11, that the flange of the coin may pass between the beaks 10 of the feelers, so that these will then grip the coin within its flange. The coin reaches almost simultaneously the pawl 7, whereby its downwards movement is stopped, but the coin will now move to the left (Fig. 1) on the 15 pawl, guided by the beaks of the feelers gripping within the flange of the coin, until it is no more supported by the pawl. At this moment the centre of the pawl (its centre of gravity) is obliquely below to the left of 20 the place where the beaks of the feelers grip the coin closely within its flange, and the consequence thereof is that the coin now suddenly in consequence of the gravity moves downwards with the edges of its flange sliding 25 along the said beaks and simultaneously therewith swings counter-clockwise, during which swinging movement the coin by acting from below against the bevelled underedges 8 of the pawl 7 turns the pawl clockwise.

30 The coin will then with a certain kinetic energy strike against the two beaks of the feelers at the moment its centre of gravity is vertically below the gap between the beaks of the feelers. By this action the feelers are 35 turned so much that they will release the coin which will fall vertically downward, whereby it is made to fall to the right of the wall 13, whence it is in any suitable manner conducted further to release the opening member of the machine. As soon as the coin has 40 fallen, the pawl 7 will by its gravity swing back into its normal position.

If instead of a coin with flange a coin without flange is inserted into the machine, 45 such a coin will after abutting against the pawl 7 roll to the left on the same without being acted upon by the beaks of the feelers 9. The coin will in this manner roll off the pawl in the said direction and will fall down 50 in such a manner that it passes to the left along the partition 13, to thence be conducted out of the machine.

Some details may be changed, without departing from the scope of the invention.

55 I claim:

A releasing mechanism for vending machines for distinguishing between flanged and flangeless coins comprising a coin chute, a pair of feelers having beaks upon their 60 lower ends and directed toward each other and having a gap therebetween, means for pivotally supporting the feelers, a partition below the beaks, a stop member mounted below the beaks and in offset relation with respect to the gap between said beaks, said mem-

ber being adapted to engage a flangeless coin introduced in said chute to influence the same passing between the beaks to fall to one side of the partition, and to engage the flange of a flanged coin, the kinetic action of the 70 flanged coin subsequently causing the beaks to release the flange to permit said coin to fall to the opposite side of the partition, and yieldable means holding the beaks against the chute.

In testimony whereof I affix my signature.
HANS CHRISTIAN HANSEN.
